Inventor:

Ernest W. Gates

By Knight, Brown, Quincy, May

Atty's.

UNITED STATES PATENT OFFICE.

ERNEST W. GATES, OF WRENTHAM, MASSACHUSETTS.

GUARD FOR CIGAR CUTTERS.

Application filed December 14, 1922. Serial No. 606,850.

To all whom it may concern:

Be it known that I, ERNEST W. GATES, a citizen of the United States, residing at Wrentham, in the county of Norfolk and 5 State of Massachusetts, have invented new and useful Improvements in Guards for Cigar Cutters, of which the following is a specification.

This invention relates to a cigar-cutter of 10 well known construction, comprising a casing having a cigar-receiving orifice in its top plate, a spring-actuated knife movable within the casing in a plane parallel with the top plate, and let-off means within the 15 casing, operable by the insertion of the pointed end of a cigar in said orifice to release the knife and cause it to clip off the pointed end. The arrangement is such that the tip of a finger inserted carelessly in said 20 orifice is liable to be clipped off. Accidents of this kind are not uncommon, particularly when children experiment with the cutter.

The object of the invention is to provide a guard which is self-attaching to the top 25 plate, without change or modification of any part of the cutter, and without the employment of positive fastening means, the guard being adapted to receive the major portion of a cigar and prevent the possibility of the 30 insertion of a finger tip in the orifice, and also adapted to be quickly installed on the cutter without liability of accidental displacement.

Another object is to provide a guard characterized as above stated, and adapted to 35 be moved endwise and actuate the let-off means, without requiring pressure on the cigar to accomplish this result, so that liability of injuring the wrapper by pressure 40 thereon is prevented.

I accomplish these and other related objects by the improved guard construction hereinafter described and claimed.

Of the accompanying drawings forming a 45 part of this specification,—

Figure 1 is a perspective view of a guard embodying the invention.

Figure 2 shows, partly in section and partly in elevation, a cigar-cutter of well 50 known construction, and, in section, the guard of my invention engaged with the top plate of the cutter.

Figure 3 is a fragmentary view similar to portions of Figure 2, showing the guard depressed to actuate the let-off means. 55

The same reference characters indicate the same parts in all the figures.

In the drawings, *a* represents the casing of an automatic cigar-cutter having a top plate in which is a cigar-receiving orifice *b*. 60 Within the casing and spaced below the orifice is a horizontally movable clipping knife *c*, actuated by a spring, not shown. Interposed between the path of the knife and the top plate is a member *d* of a let-off mechanism, said member having a smaller orifice *e*, formed to receive the pointed end portion of a cigar *f*, the member *e* being normally supported in the position shown by Figure 2, with its upper side 65 slightly spaced below the top plate, and its lower side slightly spaced above the path of the knife. The member *d* is movable downward by the pressure of the cigar upon it, to the position shown by Figure 3, this 70 movement causing the knife to clip off the pointed end of the cigar. 75

The construction and arrangement are such that when the member *d* is depressed, the knife, previously restrained at one end 80 of its path, is released and is forced across the cigar to clip off its pointed end, the cutter being then automatically set for the next action.

In carrying out my invention, I provide a 85 self-attaching guard, composed of a cigar-receiving tube, having resilient means at one end, adapted to yieldingly engage the said top plate around the orifice *b*, and support the tube with its major portion projecting 90 above the top plate sufficiently to prevent the insertion of a finger tip in said orifice.

In the preferred embodiment of the invention shown, the tube, which is preferably seamless, is made of thin resilient 95 metal. The outer portion 12 of the tube is continuous, and is adapted to be grasped to manipulate the tube in engaging it with the top plate, and in subsequently exerting endwise pressure upon it, to depress the 100 member *d*, as indicated by Figure 3.

The inner end portion of the tube is peripherally discontinuous, and is composed of a plurality of resilient tongues 13, which

are inclined relative to the axis of the tube, and are bent outward at their free ends to form radial ears 14.

The tongues are spaced apart, as shown, 5 so that the discontinuous end portion is adapted to be compressed by inward pressure on the tongues until the ears 14 are adapted to pass through the orifice b. When the ears are below the top plate, the release 10 of the compressing pressure permits the tongues to spring outward, and bear yieldingly on the wall of the orifice b, the ears 14 being at the same time caused to bear on the under side of the top plate, as shown 15 by Figure 2. The tube is thus engaged with the top plate in such manner that it is firmly supported in a position perpendicular to said plate, and is not liable to be accidentally tipped. There is a sufficient space be- 20 tween the member d and the top plate to receive the ears 14, as shown by Figure 2.

The diameter of the tube is preferably such that a cigar may be inserted loosely in the tube, without necessarily contacting 25 therewith.

The described connection between the tube and the top plate permits a slight endwise depression of the tube from the position shown by Figure 2, to that shown by Figure 30 3, so that the member d may be depressed wholly by pressure exerted on the tube, without the usual pressure on the cigar, which is liable to injure the wrapper. When 35 pressure on the tube is released, the tube is restored to the position shown by Figure 2, by the upward movement of the member d from the position shown by Figure 3.

The external surface of the tube may be provided with lines 16, representing portions 40 of cigar wrappers, so that the tube simulates a bunch of cigars. This simulation may be heightened by coloring the said external surface like a cigar wrapper.

Advertising matter may be placed on the 45 external surface of the tube.

I have found that, while it is a comparatively easy matter to engage the tube with the top plate, separation of the tube from the plate is considerably more difficult.

It will be seen that the described guard 50 is adapted to be quickly and conveniently engaged with the top plate of a standard cigar-cutter, without any change or adaptation of any part of the cutter, and without the employment of positive fastening means. 55

I claim:

1. A self-attaching guard for cigar-cutters, composed of a cigar-receiving tube having resilient means at one end, adapted to yieldingly engage the top plate of a cigar-cutter around the margin of a cigar-receiving 60 orifice therein.

2. A self-attaching guard for cigar-cutters, composed of a tube adapted to receive a cigar, and provided at one end portion with resilient tongues, adapted to yieldingly engage the top plate of a cigar-cutter, around the margin of a cigar-receiving orifice therein. 65

3. A self-attaching guard for cigar-cutters, composed of a tube adapted to receive a cigar, one end portion of the tube being composed of resilient tongues inclined relative to the axis of the tube, and bent outward at their free ends, said tongues being 70 adapted to yieldingly engage the top plate of a cigar-cutter, around the margin of a cigar-receiving orifice therein. 75

4. A self-attaching guard for cigar-cutters, composed of a cigar-receiving tube, 80 provided at one end portion with means for slidably and yieldingly engaging the top plate of a cigar-cutter, around a cigar-receiving orifice therein, the arrangement being such that said tube is capable of a 85 limited endwise movement to actuate a member of the cutter.

In testimony whereof I have affixed my signature.

ERNEST W. GATES.
